(57) **CLAIM**

The ornamental design for an electrical box interface flange, as shown and described.

DESCRIPTION

This application claims the benefit of application Ser. No. 17/861,779 now utility patent U.S. Pat. No. 11,476,651 B1—Finish Material Interface Flange—George Emmanuel Mon as sole inventor and application Ser. No. 17/723,176 now utility patent U.S. Pat. No. 11,424,604 B1—Flush Wallplate Electrical Box Assembly—George Emmanuel Mon as sole inventor.

FIG. 1 is a front perspective view of a first embodiment of the electrical box interface flange;

FIG. 2 is a back perspective view thereof;

FIG. 3 is a front-side perspective view, the opposite front-side being a mirror image, thereof;

FIG. 4 is a back-side perspective view, the opposite back-side being a mirror image thereof;

FIG. 5 is a front view thereof;

FIG. 6 is a back view thereof;

FIG. 7 is a side view thereof;

FIG. 8 is a front view, shown in an environment;

FIG. 9 is a back perspective view, shown in an environment;

and,

FIG. 10 is front, perspective and sectional view taken along lines 10-10 in FIGS. 8 and 9; and shown in an environment. In FIGS. 8, 9 and 10, the broken lines are for the purpose of illustrating environment only that form no part of the claimed design.
